Application October 17, 1945, Serial No. 622,921

7 Claims. (Cl. 102—71)

(Granted under Title 35, U. S. Code (1952), sec. 266)

This invention relates to a combination fuze for a bomb for destroying enemy ordnance, storage depots, and the like and is adapted to be dropped from an aircraft in flight and fire upon impact with the target or by an electrical impulse. When the fuze is fired electrically, either on striking the target or in the vicinity thereof, as the case may be, it will be understood that the bomb is preferably mounted on a robot plane or glider plane and means are employed whereby the bomb is exploded electrically on impact with the target or electrically by remote control apparatus within the plane as is well known in the art to which the invention pertains. The device of the present invention may also be used for destroying aircraft, secret equipment and the like employed thereon by demolition, in the event that the aircraft has been disabled due to enemy gun fire and the craft is likely to fall into enemy hands. Under such conditions it has been found necessary to destroy the plane and equipment by demolition and for this purpose it is necessary to provide a fuze which can be armed and fired after a predetermined period of time has elapsed sufficient to allow time for the crew members of the plane to bail out before the demolition charge is fired.

One of the objects of the invention is the provision of a new and improved fuze for a bomb adapted to be detachably secured to a bomb casing and having arming means arranged therein adapted to be released and actuated to an armed position during the free flight of the bomb toward the target, and firing means therefor including an electroresponsive detonator and impact firing means for firing the explosive charge disposed within the bomb.

Another object of the invention is the provision of a new and improved fuze for a bomb having slideable arming means releasably arranged therein in an initial safe position and including means for releasing the slideable arming means during the free flight of the bomb toward the target.

Another object of the invention is the provision of a new and improved fuze for a bomb having a slideable arming member arranged therein in which the arming member is maintained in an initial safe position and thereafter locked in an armed position.

Another object of the invention is the provision of a fuze having a slideable arming member arranged therein and means rotatably supported on the fuze and adapted to release the arming member when rotated a predetermined amount whereby the fuze is armed, the fuze also being provided with dual means for firing the explosive charge within the fuze after the fuze has been armed and upon impact of the bomb with the target.

Another object of the invention is the provision of a new and improved fuze for a bomb, the fuzed bomb being adapted to be arranged in a glider plane having inertia generator device therein for generating a voltage sufficient to fire the bomb upon impact of the bomb with the target or fired at will by a radio signal on or within the vicinity of the target.

A further object of the invention is the provision of a new and improved fuze for a bomb having normally locked rotatable arming means and a slideable arming member maintained in an initial safe position by the arming means and adapted to move to an armed position after the rotatable arming means has been released and rotated a predetermined amount.

Still further objects, novel features and advantages of the invention will become apparent from the following description taken in connection with the accompanying drawings, wherein:

Fig. 1 is an elevational view partly broken away of a fuze constructed in accordance with the present invention and showing a fragmentary portion of a bomb and the manner in which the fuze is attached thereto;

Fig. 2 is a central longitudinal sectional view taken substantially on line 2—2 of Fig. 1;

Fig. 3 is a front elevational view of Fig. 1;

Fig. 4 is a view similar to Fig. 2 but showing the fuze in an armed position and the conductor plug thereof replaced by a cap;

Fig. 5 is a fragmentary sectional view taken on line 5—5 of Fig. 4;

Fig. 6 is an enlarged sectional view taken on line 6—6 of Fig. 4;

Fig. 7 is an enlarged sectional view taken on line 7—7 of Fig. 4;

Fig. 8 is an enlarged fragmentary sectional view of a portion of the fuze showing the arming member locked in an armed position;

Fig. 9 is an enlarged sectional view taken on line 9—9 of Fig. 2;

Fig. 10 is an elevational view of a combination mine and bomb showing the manner in which the device of the present invention is attached thereto;

Fig. 11 shows in diagrammatic form a circuit arrangement suitable for operating the fuze from a current generator; and

Fig. 12 shows in diagrammatic form a circuit arrangement for operating the fuze by a radio signal.

Referring to the drawings in detail for a more complete understanding of the invention, the fuze 10 disclosed thereon comprises a casing or housing 11 composed of any material suitable for the purpose such, for example, as steel, brass or the like.

As shown on the drawings, especially Figs. 1, 2 and 4 thereof, the housing 11 of the fuze 10 is detachably secured to a bomb casing 12 by an adapter generally indicated by the reference character 13 comprising an annular member 14 having a threaded nipple 15 integrally formed thereon and adapted to have threaded engagement with a threaded opening 16 provided in the casing 12 of the bomb. A plurality of recesses 17 are provided in the annular member 14 whereby a spanner wrench or the like may be employed for screwing the adapter 13 into the threaded opening 16 provided in the casing 12 of the bomb.

The housing 11 is provided with an enlarged head 18 having a reduced screw threaded portion 19 formed thereon adapted to engage an internally threaded portion 21 provided on the adapter 13 whereby the fuze 10 is detachably secured to the adapter. The housing 11 is also provided with a cylindrical member 24 integrally formed on the portion 19 thereof and extending a predetermined distance into a tube 25, the tube being secured to the adapter 13 in any suitable manner, thereby providing a chamber for enclosing the housing 11, and also isolating a demolition charge 26 therefrom. Secured to the lower portion of the cylindrical member 24 of the housing 11 is a tubular member 27 having one end thereof closed as at 28 thereby to receive and support an ex-

70

plosive booster charge 29 arranged within an annular container 31, the container being in registered engagement with a block 30 secured to the lower end of the cylindrical member 24 of the housing 11. The tubular member 27 is secured to the cylindrical member 24 in any suitable manner but preferably by threading the member 27 into a threaded portion 32 provided on the lower end portion of the cylindrical member 24.

A plunger or arming member 33 is slideably arranged within a cutout portion 34 also provided in the lower end portion of the member 24, and the block 30 is arranged in abutting relation with respect to the lower end portion of the member 24 being secured thereto by screws 36 thereby slideably maintaining the arming member within the cutout portion 34. The arming member 33 is urged toward an armed position by a pair of springs 37 enclosed in tubes 38, one end of each tube being closed as at 39. The other end of each tube 38 is respectively secured within a recess 41 provided in the plunger 33 thereby providing means for moving the plunger to an armed position after the plunger has been released, as will be hereafter more fully described. The arming member 33 is releasably locked in an initial safe position as shown on Fig. 2 of the drawings by a moveable firing pin 42 having one end thereof extending a predetermined distance into a recess 43 arranged within the arming member. The arming member 33 is also provided with a bore 44 having a sensitive primer 45 disposed therein which is adapted to be moved into alignment with a lead-in charge 46 arranged with an opening 47 provided in the block 30 thereby to establish an operative explosive train between the primer 45 and the booster charge 29 when the arming member is in armed position.

As shown on Figs. 2 and 4 of the drawings, the firing pin 42 is rigidly supported within a sleeve 48, the sleeve having threaded engagement at 50 with a portion of a bore 49 extending through a nipple 51. The nipple is secured within the housing 11 in any suitable manner preferably by being threaded into an opening 52 provided in the housing 11. The sleeve 48 is provided with a reduced portion 53 formed thereon and extends through an opening 54 arranged in an annular member 55 provided in the member 51 and disposed within the bore 49. The sleeve 48 is adapted to engage the annular member 55 thereby preventing further movement of the firing pin into the recess 43 provided in the arming member, and thus the arming member is maintained in initial safe position by the firing pin until the firing pin has been withdrawn from the recess 43.

Secured on one end of the sleeve 48 is a propeller 56 having a conical hub 57 and a plurality of blades 58 extending therefrom adapted to rotate the sleeve during the free flight of the bomb toward a target. The propeller 56 is secured to the sleeve in any suitable manner but preferably by a dowel pin 59 forced into an aperture in the end of the sleeve and extending into an opening 61 provided in the hub 57 thereby locking the propeller to the sleeve for rotative movement therewith. The propeller 56 is maintained in locked position on the sleeve 48 by a bolt 60. By this arrangement it will be understood, however, that rotative movement is imparted to the sleeve 48 by the propeller as the result of the pressure of the air against the propeller blades 58 during the free flight of the bomb toward a target. As the sleeve rotates within the threaded portion of the bore 49 outward movement is also imparted thereto due to a complementary threaded portion on the sleeve engaging the threaded portion of the bore 49 and also due to the rotation imparted thereto by the propeller as heretofore described. Thus the firing pin secured to the sleeve is withdrawn from the recess 43 provided in the arming member and the arming member is released and is urged under tension of the springs 37 to the armed position as shown on Figs. 4, 6, 7, and 8 of the drawing. It will be understood, however, that the propeller is adapted to make

a predetermined number of revolutions before the firing pin is withdrawn from the arming member, after which a stop 62 secured on the other end of the sleeve 48 engages the annular member 55 thereby preventing further movement of the sleeve and thus the striker 63 of the firing pin 42 is maintained in predetermined spaced relation with respect to the sensitive primer 45 and upon impact of the bomb with the target the striker 63 fires the primer 45.

10 The firing pin 42 is adapted to move freely through a bore 64 provided in the portion 24 of the housing 17 and when the arming member 33 is in an armed position the sensitive primer, lead-in charge and booster charge are in line with the firing pin and upon impact of the bomb 15 with a target, the threads 50 are sheared and the striker 63 is driven through the bore 64 and into the sensitive primer with sufficient force to fire the primer thereby to initiate firing of the demolition bomb.

It will be understood, however, that selective operation 20 of the fuze may be obtained by arranging the sleeve member 48 in such a manner as to permit the threads 50 to shear and the fuze to function on impact with targets comprising different degrees of resistances, and also so constructed as to function at one velocity and not function at another velocity. For example, the fuze may be so constructed as not to function on water upon impact therewith when the bomb is dropped from a distance of 5,000 feet, but will function on light armor plate when dropped from a distance of 50 feet. If desired, the fuze 25 may be so constructed as not to function upon impact with a body of water when the bomb is dropped thereon at an altitude of 5,000 feet, but will function upon impact with a body of water when dropped from an altitude greater than 5,000 feet.

30 As shown on Fig. 7 of the drawings the arming member 33 is locked in the armed position by a pair of detents 65, each detent being provided with a reduced portion 66 adapted to extend into a pair of openings respectively arranged in the portion 24 of the housing 11 after the arming member has been released and has moved to an armed position. The detents are slideably arranged 35 within a pair of bores 67 provided in the arming member 33 and adapted to be urged outwardly by a spring 68 disposed within the bore and having each end thereof respectively engaging a detent 65 thereby locking the arming member in an armed position. To assure locking of the arming member in an armed position, as shown on Fig. 8 of the drawing, a spring pressed detent 69 is employed. The detent 69 is arranged in a bore 71 provided in the block 30 and is normally maintained within the bore by abutting engagement with the arming member when the arming member is in the initial safe position. It will be understood, however, that when the arming member has been released and moves to an armed position the detent 69 is adapted to be urged into a recess 72 arranged in the arming member by a spring 73 thereby providing additional means for locking the arming member in an armed position.

As shown on Fig. 1 of the drawings means are provided whereby rotation of the propeller 56 is prevented and arming of the fuze will not occur until the propeller has been released. The releasing means including an annular member 74 surrounding the portion 19 of the housing 11 and held in clamping engagement with the member 14 of the adapter 13 by the enlarged head 18 of the housing. The annular member 74 has a bifurcated retaining member 75 formed thereon for detachably supporting a releasing device 76, the releasing device including a rod 77 resting in the bifurcated portion and having one end thereof extending between a pair of the propeller blades 58 and the other end having a supporting pin 78 secured thereto in any suitable manner whereby the releasing device 76 is supported in operative relation with respect to the propeller. The pin 78 supporting the rod 77 is releasably maintained in a pair of registering

apertures 79 disposed in the retaining member 75 by a frangible wire 81 composed of any material suitable for the purpose such, for example, as lead, the wire being adapted to pass through an eye 82 formed on the upper end of the pin 78 and also adapted to pass about the bifurcated portion of the retaining member 75, the free end thereof being secured together as at 83 thus maintaining the rod 77 in locking relation with respect to the propeller 56.

One end of a safety wire 84 is secured to the eye 82 of the pin 78 as shown in Figs. 1 and 3 for forcibly removing the releasing device 76 from the retaining member thereby to arm the fuze, the other end of the safety wire 84 being adapted to extend into the aircraft or robot plane, as the case may be (not shown), and be actuated in any suitable manner such, for example, as by a mechanical device or, if desired, it may be manually operated. It will be understood, however, as the bomb is released from an aircraft in flight and falls away therefrom the safety wire 84 is adapted to pull the release device 77 away from the retaining member 75 thereby releasing the propeller 56 and permitting free rotative movement of the propeller during the free flight of the bomb toward the target. As the propeller rotates the sleeve secured thereto also rotates in such a manner as to move the firing pin 42 mounted in the sleeve out of the recess 43 of the arming member 33. When this occurs the arming member 33 is urged into an armed position, Fig. 4, in response to the pressure exerted thereon by the springs 68, the arming member being maintained in the armed position as heretofore described. It will also be understood, however, that the firing pin 42 is moved a predetermined distance away from the arming member during the downward flight of the bomb toward the target and upon impact of the bomb with the target the striker 63 of the firing pin 42 is driven into the primer 45 with sufficient force to cause firing thereof thus initiating firing of the lead-in charge 46, the booster charge 29, and the demolition charge 26.

While the foregoing description pertains to a fuze for a bomb which is adapted to be dropped from an aircraft in flight upon a target and to be mechanically detonated upon impact therewith, it will be understood that the fuze is also provided with an electroresponsive detonator 85 whereby the bomb may be exploded at will by remote control in response to an electrical impulse supplied thereto from any suitable source such, for example, as a radio receiving set arranged within the aircraft upon which the bomb is mounted, Fig. 12, or by an inertia operated current generator also mounted therein which is adapted to supply sufficient current through the electroresponsive detonator 85 to explode the bomb upon impact of the aircraft with the target, Fig. 11. The electroresponsive detonator 85 is arranged within a recess 86 provided in the portion 24 of the housing 11 and maintained therein by a screw threaded plug 87 having abutting relation with respect to one end of the detonator 85 and also having threaded engagement with a portion of the recess 86.

The enlarged head 18 of the housing 11 is provided with a screw threaded opening 88 having threaded therein an electrical socket 89. The socket has secured thereto a pair of electrical conductors 91, the conductors being disposed in a groove 92 provided in the housing 11 and also passing through an opening 93 provided in the plug 87. The other end of each conductor 91 is connected to the electroresponsive detonator 85 arranged within the recess 86 thereby providing a firing connection from the socket 89 to the detonator 85.

As best shown in Figs. 1, 2 and 3 of the drawings, a conductor plug 94 is connected to the socket member 89 in any suitable manner, the plug having one end of a pair of electrical conductors 90 secured thereto, the other ends of conductors being connected to a source of electrical power and to a time delay device (not shown),

such time delay device being in electrical connection with a battery or the like for supplying electrical current to the detonator 85 as the circuit is closed by the time delay device.

5 In communication with the recesses 44 and 64 in the housing 11 is a flash chamber 97 providing means whereby a flash from the detonator 85, when fired, is adapted to pass therethrough and fire the primer 45 thereby to cause the bomb to explode as is well known to those skilled

10 in the art. It will also be understood, however, that any electrically or mechanically operated time delay device suitable for the purpose may be employed in the firing circuit whereby a predetermined period of time will elapse after the time delay device has been set in operation before the detonator will be fired, thereby allowing sufficient time to elapse for the personnel of the disabled plane on which the bomb is mounted to bail out before the bomb explodes. The force of the exploding bomb will be sufficient to demolish completely the plane and the secret equipment therein, thus preventing the plane and the secret equipment from falling into enemy hands intact.

15 A protector cap 98 is secured to a threaded portion of the socket member 89 thereby enclosing the electrical contact member of the socket therein, thus preventing damage thereto and also preventing moisture and foreign matter from fouling the contact during transportation and handling. As shown on Fig. 4 of the drawings, the cap 98 may be also used when the bomb is used as a drop bomb. It will be understood, however, that when used in a robot or glider plane, the cap 98 is removed and the conductor plug 94 is connected to the socket 89 in lieu thereof when the plane in which the bomb is mounted is about to be launched or about to take off, thereby providing a firing connection by way of the cable 96 from the source of electrical power included in the firing circuit and operatively connected to a radio receiving set, inertia operated current generator or a time delay device as the case may be.

20 40 During transportation and handling of the bomb, rotative movement of the propeller 56 is prevented by a seal shown in dashed outline on Fig. 2 of the drawings and including a wire 99 which extends through an opening 101 in the housing 11 and also extends through an opening 102 in the propeller, the free end of the wire 99 being sealed within a lead disk 103. Thus the propeller is prevented from rotating and the arming member is maintained in safe position by the firing pin 42 as shown in Fig. 2 of the drawings until the seal has been broken and the wire removed.

25 50 On Fig. 11 is shown in diagrammatic form a circuit arrangement suitable for operating the fuze from an inertia operated current generator 104 such, for example, as the current generator disclosed and claimed in the co-pending application of Harold J. Plumley for Magnetic Inertia Controlled Fuze, Serial No. 535,799 filed May 16, 1944. It will be understood, however, that when the fuze is adapted to be fired by the inertia generator 104, a glider or the like may be employed, such glider having 35 arranged therein in any suitable manner the fuzed bomb and inertia generator. The glider is adapted to be released in any suitable manner from a carrier plane or the like toward the target and upon impact therewith the inertia generator is adapted to generate a voltage sufficient to fire the low energy detonator device 85 as is well known to those skilled in the art. It will be further understood that the propeller 56 is adapted to be released for rotative movement as the glider is released from the carrier plane thereby allowing free rotation of the propeller so that arming of the fuze is accomplished 45 during the free flight of the glider toward the target.

40 70 Fig. 12 shows in diagrammatic form a circuit arrangement whereby the fuze may be operated by a radio signal. It will be understood, however, that when the fuze is adapted to be fired and controlled by a radio

signal, a robot plane or the like is employed having arranged therein the fuzed bomb and a radio receiving set 105 thereby permitting the robot plane to be guided toward the target by a radio signal and also providing means whereby the bomb may be fired at will on, or within the vicinity of the target by a radio signal picked up by the receiving set 105.

Whereas, the invention has been described in detail with respect to a bomb for demolition purposes, it is obviously not so limited as it may also be employed for firing rockets, glider bombs, incendiary bombs and similar ordnance devices. The many advantages of the fuze constructed in accordance with the present invention will be readily apparent from the foregoing description, taken in connection with the accompanying drawings and, although a preferred embodiment of the device is illustrated and described, it is to be understood that changes in the details of construction and in the combination and arrangement of parts may be resorted to which fall within the scope of the invention as claimed.

The invention herein described and claimed may be manufactured and used by or for the Government of the United States of America for governmental purposes without the payment of any royalties thereon or therefor.

What is claimed as new and desired to be secured by Letters Patent of the United States is:

1. A combination fuze for a bomb adapted to be selectively fired by impact with a target or by electrical impulse receiving means, said fuze comprising a casing supported by the bomb and extending a predetermined distance therein, an explosive charge arranged within said casing, a releasable arming member slideably supported within said casing and having an explosive element positioned thereby in an initial safe position, means including a firing pin rotatably supported within said casing for releasably maintaining the arming member in said initial safe position and adapted to release said arming member to position said element in firing relation with respect to said firing pin and said electrical impulse firing means when the rotatable means has rotated a predetermined amount, means including a frangible threaded portion on said rotatable means for imparting outward movement thereto as the rotatable means rotates and constructed and arranged to be sheared as the firing pin moves to engage said element forcibly in response to said impact, means arranged within said arming member for urging said arming member from said initial safe position to said armed position when said arming member has been released, means for locking said arming member in the armed position whereby said rotatable means is adapted to fire said explosive charge as said frangible threaded portion is sheared in response to said impact should said electrical impulse means fail to receive an electrical impulse.

2. A combination fuze for a bomb adapted to be selectively fired by impact with a target or by an electrical impulse receiving means and comprising a casing supported by said bomb, a booster charge arranged within said casing, a releasable arming member slideably supported within said casing in an initial safe position, a sleeve rotatably supported within said casing, a firing pin secured within said sleeve for releasably maintaining said arming member in said initial safe position and adapted to release said arming member and arm said impulse firing means when said sleeve has been moved outwardly in response to a predetermined number of revolutions thereof during the free flight of the bomb from the aircraft toward said target, a propeller secured to said sleeve and adapted to impart rotative movement thereto, a plurality of frangible threads on said sleeve for causing said sleeve to be moved outwardly as the sleeve is rotated and constructed and arranged to be sheared as the sleeve moves inwardly in response to said impact, a pair of springs arranged within said arming member for urging said arming member to an armed position when said

arming member has been released by said firing pin, and means for locking said arming member in said armed position whereby the firing pin is adapted to fire said booster charge as said frangible threads are sheared in response to said impact should said electrical impulse means fail to receive an impulse.

3. A fuze for a bomb adapted to be dropped on a target from an aircraft in flight and comprising a casing supported by the bomb and extending a predetermined distance therein, a booster charge arranged within said casing, a releasable arming member slideably supported within said casing in an initial safe position, a sleeve rotatably supported within said casing, a firing pin secured within said sleeve for releasably maintaining said arming member in said initial safe position and adapted to release the arming member when the sleeve has been rotated a predetermined number of revolutions, means for rotating the sleeve during the free flight of the bomb from the aircraft toward said target, means including a frangible threaded portion on said sleeve for imparting outward movement thereto as the sleeve is rotated and constructed and arranged to be sheared as the sleeve moves inwardly in response to impact of said bomb with a target, means arranged within said arming member for urging said arming member to an armed position when said arming member has been released by said firing pin, and means for locking said arming member in said armed position whereby said firing pin is adapted to fire said booster charge as said frangible threaded portion is sheared and the sleeve moved inwardly upon impact of said bomb with said target.

4. A fuze for a bomb adapted to be dropped on a target from an aircraft in flight and comprising an adapter, a complementary member supported by said adapter, a container supported by said complementary member, a booster charge arranged within said container, a releasable arming member slideably supported within said complementary member in an initial safe position, a sleeve rotatably supported within said complementary member, a firing pin secured within said sleeve for releasably maintaining said arming member in said initial safe position and adapted to release the arming member when said sleeve has been moved outwardly a predetermined amount, a plurality of frangible threads on said sleeve for causing the sleeve to be moved outwardly as the sleeve is rotated and constructed and arranged to be sheared as the sleeve moves inwardly in response to impact of the bomb with said target, a propeller secured to said sleeve and adapted to impart rotative movement thereto during the free flight of the bomb toward said target, a pair of springs arranged within said arming member for urging said arming member to said armed position when said arming member has been released by said firing pin, and a pair of spring actuated detents arranged within said arming member for locking the arming member in said armed position whereby said firing pin is adapted to fire said booster charge as said frangible threads are sheared and the sleeve moves inwardly upon impact of said bomb with the target.

5. A fuze for a bomb adapted to be dropped on a target from an aircraft in flight and comprising a casing supported by the bomb, a booster charge arranged within said casing, a lead-in charge also arranged within the casing in operative relation with respect to said booster charge, a releasable arming member slideably supported within said casing in an initial safe position, a sleeve rotatably supported within the casing, a firing pin secured within said sleeve for releasably maintaining said arming member in said initial safe position and adapted to release the arming member when the sleeve has been moved outwardly a predetermined amount, means including a plurality of frangible threads on said sleeve for causing the sleeve to be moved outwardly said predetermined amount as the sleeve is rotated and constructed and arranged to be sheared as the sleeve moves inwardly

in response to impact of the bomb with said target, means secured to said sleeve for preventing further rotation of the sleeve when the sleeve has been moved said predetermined amount, a propeller secured to the sleeve and adapted to impart rotative movement thereto during the free flight of the bomb toward said target, a pair of resilient members arranged within said arming member for urging the arming member to an armed position after the arming member has been released by said firing pin, means for locking said arming member in said armed position, and a sensitive primer arranged within the arming member and adapted to be moved into registered relation with said lead-in charge when the arming member has been released and moved to said armed position, said firing pin being driven into firing engagement with said sensitive primer as said frangible threads are sheared and the sleeve moves inwardly upon impact of the bomb with said target thereby firing said lead-in and booster charges.

6. A fuze for an explosive bomb adapted to be dropped on a target from an aircraft in flight and comprising a casing supported by the bomb, a booster charge arranged within said casing, a releasable arming member slideably supported within said casing in an initial safe position and being movable to an armed position when released, a sleeve rotatably supported within the casing, means secured to said sleeve for imparting rotative movement thereto, frangible threaded means on said sleeve for co-acting with complementary means on the casing for causing outward movement of the sleeve as the sleeve is rotated, a primer carried by said arming member and arranged to be moved into firing relation with said charge when the arming member is in said armed position, and a firing pin secured to and movable with said sleeve for releasably maintaining said arming member in said initial safe position and for releasing the arming member when the sleeve has been moved outwardly a predetermined amount, said firing pin being driven into firing engagement with the primer as said frangible threaded means is sheared upon inward movement of the sleeve in response to impact of the bomb with said target thereby to fire said charge and explode the bomb.

7. A combination fuze for an aircraft dropped bomb

comprising, in combination, a casing supported by the bomb, an explosive charge arranged within said casing, a primer, a releasable arming member for moving said primer from a safe position into operative firing relation with respect to said charge when the member is released, means including a firing pin arranged initially in locking engagement with said arming member for retaining the arming member in safe position until the pin is withdrawn therefrom, means forming a frangible threaded connection between the casing and said retaining means for withdrawing the firing pin when the retaining means is rotated a predetermined number of revolutions, means including a propeller operatively connected to said retaining means for causing said predetermined rotation thereof during the free flight of the bomb through the air, an electroresponsive detonator for firing said primer, means forming a passageway for connecting said detonator in firing relation with respect to said primer when said firing pin is withdrawn, and means including an inertia operated current generator for supplying an electrical firing impulse to said detonator as the bomb strikes the target, said threaded connection being sheared for enabling said firing pin to be driven into firing engagement with the primer in response to said impact, thereby to explode the bomb when said generator fails to fire the detonator.
